UNITED STATES PATENT OFFICE.

WARREN F. FRASER, OF DORCHESTER, MASSACHUSETTS.

TOOL-DRIVER.

1,242,933.

Specification of Letters Patent. Patented Oct. 16, 1917.

Application filed December 8, 1914. Serial No. 876,126.

To all whom it may concern:

Be it known that I, WARREN F. FRASER, a subject of George V, King of Great Britain, residing at Dorchester, county of Suffolk, Commonwealth of Massachusetts, have invented certain new and useful Improvements in Tool-Drivers, of which the following is a specification.

This invention relates to tool drivers and particularly to a fluid impelled screw driver wherein some elastic fluid such as compressed air is directed against a rotor operatively connected with a tool spindle to impart rotation thereto.

The tool illustrated in my present invention is especially designed for use upon piano actions and the like where the screws to be set are adjacently disposed in a line across the action. In this class of work the tool is held in one hand and the screws may be set with the other hand so that a series of screws may be successively positioned and rapidly driven. The positive control of the impelling agent which rotates the tool spindle is of the utmost importance in this class of work. Where a screw is inaccurately started it must be instantly withdrawn and properly restarted. This involves changing the direction of impact of the impelling agent to reverse the rotor and instantaneously retract the screw. The speed with which the tool spindle may be reversed to withdraw instead of continuing to drive the screw is dependent upon the responsiveness of the controlling element for the impelling agent to a positive manipulation. Inasmuch as the nature of the work requires the free use of both hands in the manipulation of the tool, it is desired that the effective directions of fluid impact upon the rotor shall be capable of instant control from a single control element and that this element shall be located in conveniently operable position relative to the hands, so as to permit ready and positive adjustment thereof without removing the hands from the tool.

It is furthermore important that the rotation of the parts be imparted or caused to cease instantly. I therefore provide a rotor unit in which opposed sets of buckets are disposed on a single element so that the reverse impulse not only effects the reverse but instantly stops the original directive tendency.

To the end therefore of providing a tool of this nature I have devised my present

invention. The tool of this invention is characterized by the fact that the impelling agent is controlled from a single reversible control element positioned in conveniently operable relation to the hand of the operative. This permits change of the direction of drive by simple reversal of the control element without necessitating removal of the hands from the tool. Provision is also made for reducing the speed and increasing the power of the drive from the rotor to the tool spindle. These and other features which will appear more fully herein-after are secured in the tool of the present invention.

The construction and operation of my invention will be more fully disclosed in the specification which follows. In the drawings forming a part of that specification I have shown a form of tool which is in itself a clear illustration of the principles involved and which has proven satisfactory in practical use and well adapted to the requirements of manufacture. Throughout the specification and drawings like reference numerals are correspondingly applied and in these drawings:

Figure 1 is an elevation of a tool in accordance with my invention.

Fig. 2 is a plan view thereof with one of the cover plates removed.

Fig. 3 is a side view of the rotor unit and associated parts, the casing being omitted.

Figs. 4 and 5 are detail sections on the lines 4-4 and 5-5 respectively of Fig. 2.

Figs. 6, 7 and 8 are detail views of the chuck, Figs. 6 and 7 being sections at right angles to each other and Fig. 8 being an elevation.

Fig. 9 is a detail view of the detent for holding a tool in the chuck, and

Fig. 10 is an elevation of one of the tools.

I have indicated at 1 a casing, in the form of a band having its ends detachably connected with each other by any suitable connection. The casing has a removable substantially fluid tight fit upon the head of the tool. This head consists of a pair of spaced annular cover plates 3 removably connected with each other by a plurality of bolts 4. The opposed faces of the plates 3 have each an annular shoulder 5 against which the casing 1 is removably seated. The plates 3 and casing 1 therefore define a substantially fluid tight chamber in which the rotor unit and associated parts are located.

The rotor unit consists of a single rotor element mounted within the casing on a shaft 6 journaled in the plates 3. The rotor has a pair of adjacent peripheral series of fluid impact elements or buckets 7 and 8 disposed in co-axial relation to each other. The buckets of one series are set at opposite angles to the buckets of the adjacent series.

The rotor unit is rotated in one direction or the other by delivering an elastic fluid agent, preferably compressed air, against one or the other of these bucket series. The arrangement is such that air may be directed against either bucket series to impart to the rotor its initial directive tendency. The rotor is reversed by simply shutting off the air to the bucket series initially driving and directing the air against the initially ineffective series to cause that series to assume the drive and rotate the rotor in a direction opposite to the initial direction of rotation.

This is effected by an arrangement of air jets which selectively deliver the air to either bucket series according to the direction in which it is desired to rotate the rotor. The admission of air to these jets is controlled by a pair of valves which in turn are subject to a single control element, conveniently disposed so that it may be manipulated without removing the hands from the tool.

In the tool illustrated I have shown the rotor as driven from two pairs of oppositely directing jets 9 and 10 and 11 and 12 all connecting with a single intake. The jet pipes 9 and 12 are arranged at opposite sides of the rotor in a suitably covered casing 13 carried by one of the plates 3 and have each an exposed delivery end in proximity to a bucket series. The pipes 10 and 11 cross each other within the casing 13 and between the pipes 9 and 12 and have their exposed delivery ends each directing against a bucket series. The jets 9 and 10 therefore constitute a couple delivering in a common direction to rotate the rotor in one direction and the jets 11 and 12 constitute a couple delivering in the opposite direction to rotate the rotor in reverse direction.

The compressed air or other elastic fluid is supplied to these jets by means of an intake pipe 13¹ connecting with any suitable source of supply and delivering into a common chamber 14 within the casing 13. The passage of the air from the chamber 14 is controlled by a pair of valves 15 normally sealing a pair of air passages 16 and normally held against their seats by a pair of springs 17 interposed between the valves and the upper plate 3.

The passages 16 are simply holes bored through a pair of castings 18 threaded into the casing 13.

The passages 16 connect each with a separate air conduit 19—20 cored into the casing

13 by means of a plurality of lateral ports 21¹ drilled through the walls of the castings 18. Each conduit opens up into a separate chamber 21—22 with which the pairs of jets 9—10 and 11—12, respectively, 70 connect.

The valves 15 are carried by stems 23 passing through the air passages 16 in the castings 18 and projecting slightly beyond the castings 18 so as to lie in operating contact relation to a manually operated reversible control element pivoted on one of the plates 3.

This control element consists of a contact piece or head 25 having trunnions 26 whereby it is rockingly mounted in bearings 27 on one of the plates 3. The contact element 25 is normally disposed in horizontal non-contacting position relative to the valve stems 23. When it is desired to impart rotation to the rotor the contact element is rocked on its pivot to cause its head to depress the proper valve stem against the tension of its spring 17 and unseat its valve 15. This permits air to pass to the chamber 21—22 which that particular valve controls and from thence through the jet pair connecting with said chamber to the particular bucket series driven from that jet pair. The contact head is held in the position to which it is rocked as long as it is desired to rotate the rotor in that particular direction. When it is desired to reverse the rotor, the contact element is rocked in the opposite direction to release the stem initially depressed and depress the other stem, thereby closing the jet pair initially effective and admitting air to the jet pair heretofore ineffective. This causes the bucket series against which said last named jet pair delivers to assume the drive and reverse the rotor.

These rocking movements of the contact element may be conveniently effected by means of an operating stem 28 connected thereto and projecting through an elongated slot 29 in one of the plates 3. The stem 28 may carry a ring 30 at its free end in which the index finger of one hand may be engaged to positively rock the contact element and hold it in the position to which it is rocked while the tool is held with the remaining fingers and thumb of that hand. This leaves the other hand free to set the screw being driven.

The rotor is operatively connected with the tool spindle 31 in any suitable manner. This connection may conveniently be effected by a series of gears between the rotor shaft 6 and the tool spindle. The rotor shaft has a pinion 32 which meshes with a large gear 33 on a counter-shaft 34 journaled in the plates 3. The rotation of the shaft 34 is transmitted to a third shaft 35 journaled in the plates 3 by a pinion 36 on said shaft 34 meshing with a large gear 37 on the shaft 35. The rotation of the shaft 35 is transmitted to

the tool spindle by a pinion 38 on said shaft 35 meshing with a large gear rigidly mounted on the tool spindle. The gear train 33, 36, 37 and 38 acts to reduce the speed of the spindle and increase the power of the drive. Obviously this gear train might be dispensed with if desired without departing from the spirit of this invention, and the spindle might be driven by simply placing the pinion 32 on the rotor shaft in such a position as to mesh with the gear 39 on the tool spindle. The tool spindle 31 is journaled at each end in suitable thrust bearings 31 and is incased within a sleeve 40 integral to one of the plates 3. The upper end of the spindle is enlarged as indicated at 41 to provide a chuck. This enlargement has an axial bore 41¹ in which different tools may be inserted. A screw 42 set flush in a hole let in the enlarged end of the spindle serves to secure one end of a spring 43 for yieldingly urging a detent 44, to which the other end of the spring is secured, into locking engagement with an annular groove 45 in a tool 46. The body of the spring 43 lies in a saw cut 47 connecting the screw 42 and detent 44. The inner end of the tool 46 is flattened on two sides as indicated at 47¹ to enable it to shoulder in a slot 48.

30 A lateral bore 48 intersects the axial bore 41¹ at its lower end. The flattened portions 47¹ of the tool 46 fit snugly in this bore 48 so as to couple the tool to rotate with the spindle.

35 In use the intake connection 13¹ is connected by means of a flexible tube or the like with a source of compressed air or other elastic fluid. The fluid is admitted to the casing 13 and passes through one pair or the other of the two pairs of jet pipes, according to which valve is opened, and delivers against one of the two bucket series. This rotates the rotor and this rotation is transmitted to the tool spindle through the series of gears described to rotate the tool spindle in the same direction as the rotor is rotating. This direction of rotation is maintained so long as the valve stem initially depressed by the contact element is held down. When it is desired to stop the rotor, the contact element is released and the spring of that valve stem which was depressed exerts its tension to return the valve stem to normal position, thus seating the valve and closing that particular jet pair. When it is desired to reverse the direction of rotation, as where a screw is to be withdrawn, the control element is rocked in the opposite direction to open the previously closed valve and close the previously opened valve. This cuts off the air to the jet pair initially delivering and diverts it to the other jet pair, thereby operating upon the previously ineffective bucket series and reversing the rotor. This reversal is effected practically instantly and

stops the initial directive tendency of the rotor and immediately causes it to commence to rotate in the opposite direction. The reversal of the contact element being effected by simple movement of the index finger, 70 leaves the remaining fingers and thumb of that hand free to hold the tool and does not require the use of the other hand which is free to position the screws.

75 While I have shown and discussed my invention in its application to the driving and removal of screws it will be understood that I do not limit myself to this or any other application but reserve the right to use the invention in any capacity where it would satisfactorily perform its intended functions.

80 Various modifications in the form and construction of the tool may obviously be resorted to if within the limits of the appended claims.

85 What I therefore claim and desire to secure by Letters Patent is:

1. A device of the class described comprising a casing, a tool spindle rotatably mounted therein, a rotor element operatively connected to said spindle having a pair of opposite bucket series, a pair of oppositely directing jets disposed for delivery in the path of said bucket series, an air intake, a pair of 90 valves for positively controlling the delivery of air from the intake to said delivering jets, and a reversible control associated with said valves and operative upon one valve in one direction of its movement and upon the 95 other valve in the other direction of its movement.

2. In a driver of the class described, a reversely rotatable tool spindle, a rotor therefor having a pair of oppositely effective 105 bucket series, a pair of jets disposed for delivery in the path of one bucket series, a pair of oppositely directing jets disposed for delivery in the path of the other bucket series, a casing having an air intake and a 110 pair of air passages independently connecting each with a pair of jets, a pair of valves controlling said passages, and a single reversible control disposed in operating contact relation to the stems of said valve and operable upon one valve in one direction of 115 its movement and upon the other valve in the opposite direction of its movement.

3. In a driver of the class described, a reversibly rotatable tool spindle, a rotor therefor having a pair of oppositely effective bucket series, a speed reducing gearing operatively connecting said rotor and spindle, a pair of jets disposed for delivery in the path of one bucket series, a pair of oppositely 120 directing jets disposed for delivery in the path of the other bucket series, a casing having an air intake and a pair of air passages independently connecting each with a 125 pair of jets, a pair of valves controlling said 130

passages, and a single reversible control disposed in operating contact relation to the stems of said valve and operable upon one valve in one direction of its movement and upon the other valve in the opposite direction of its movement.

4. In a driver of the class described, a reversibly rotatable tool spindle, a rotor therefor having a pair of oppositely effective

10 bucket series, a series of oppositely directing jets disposed for delivery in the path of a bucket series, an air intake connecting with said jet series, a pair of valves controlling the delivery of air to said jets and having 15 their stems exposed, a reversible control having a pivoted valve stem contacting part and a manually operated part connected with said stem contacting part and said control effective to depress one valve stem in one 20 direction of its movement and to depress the other stem in the opposite direction of its movement.

5. In a driver of the class described, a rotatable tool spindle, a reversible rotor therefor, an air intake, an air delivery for rotating the rotor in one direction and an independent air delivery for reversing the 25 rotor a pair of valves normally closing said deliveries, and a reversible control for selectively opening either valve.

6. In a driver of the class described, a rotatable tool spindle, a reversible rotor therefor, an air intake, an air delivery for ro-

tating the rotor in one direction and an independent air delivery for reversing the 35 rotor, a casing having a common chamber with which said intake connects, a pair of valves controlling said chamber and each connecting with a delivery, and a reversible control effective upon one valve in one direction of its movement and effective upon the other valve in the opposite direction of its movement.

7. In a driver of the class described, a rotatable tool spindle, a reversible rotor 45 therefor, an air intake, a pair of air deliveries, one effective to rotate the rotor in one direction and the other effective to reverse the rotor, a casing having an air chamber with which said intake connects 50 and having a pair of air passages leading from said chamber and terminating each in a delivery chamber with each of which an air delivery connects, a pair of valves controlling each an air passage, and a single 55 control element reversibly mounted in selective controlling relation to said valves and effective upon one valve in one direction of its movement and upon the other valve in the opposite direction of its movement. 60

In testimony whereof I affix my signature in presence of two witnesses.

WARREN F. FRASER.
